UNITED STATES PATENT OFFICE.

FRANK D. COLLINS, OF WASHINGTON, DISTRICT OF COLUMBIA.

ILLUMINATING APPARATUS.

1,412,675.

Specification of Letters Patent. Patented Apr. 11, 1922.

Application filed March 25, 1921. Serial No. 455,605.

To all whom it may concern:

Be it known that I, FRANK D. COLLINS, a citizen of the United States, residing at Washington, in the District of Columbia, 5 have invented new and useful Improvements in Illuminating Apparatus, of which the following is a specification.

The object of my present invention is the provision of an illuminating apparatus for 10 coloring in an attractive manner a frosted glass behind which the apparatus is arranged or for illuminating in colors a sign or show card or a show window, or for bringing about attractive lighting effects on a 15 stage with a view to enhancing the beauty of costume dances, and for other lighting effects.

To the attainment of the foregoing, the invention consists in the improvement as 20 hereinafter described and definitely claimed.

In the accompanying drawings, forming part of this specification:—

Figure 1 is a vertical section, partly in elevation, of the apparatus constituting the 25 best practical embodiment of my invention that I have as yet devised.

Figures 2 and 3 are sections taken in the planes indicated by the lines 2—2 and 3—3, respectively, of Figure 1.

30 Figure 4 is an enlarged perspective of the bracket comprised in the apparatus.

Figure 5 is a horizontal section taken on the line 5—5 of Figure 1, looking downwardly.

35 Figure 6 is a horizontal section taken through a modified prism hereinafter explicitly referred to.

Similar numerals designate corresponding parts in Figures 1 to 5 to which reference 40 will first be made.

Among other elements the apparatus illustrated includes a casing 1 having ventilating openings 2 and superimposed on and fixed with respect to an appropriate base 3. Also 45 superimposed on and fixed to the base 3 is a motor 4 which may be of any description compatible with the purpose of my invention. The casing 1 is shown as provided with side doors 5 to permit of ready access being 50 gained to the interior of the casing. This, however, is not of the essence of my invention and therefore it is unnecessary to further describe the casing 1 and the doors 5 except to say that when the latter are employed they are normally secured in closed 55 position by appropriate fasteners 6.

Arranged in the casing 1 and fixed on the base 3 is a bracket 7 on which is an overhanging arm 8 with a vertically disposed aperture 9 therein. Carried by the upright 60 portion of the bracket 7 and disposed in front of said upright portion is a reflector 10. Movable vertically in the aperture 9 of the bracket 7 is a plunger 11 with a socket 12 in its lower end; the said plunger being provided above the bracket arm 8 with a pin 13, and being provided below the bracket arm 8 with an abutment 14 between which and the arm is interposed a tensioning spring 15. The plunger 11 is provided with 65 a series of apertures as shown in Figure 3 in any one of which the pin 13 may be placed according to the tension under which it is desired to place the spring 15.

Carried in the front wall 14' of the casing 75 1 is a tube 15', provided at its ends with double convex lenses 16, and appropriately supported in front of the lens tube 15 is a prism 17 the apex of which is arranged immediately adjacent to the forward lens 16 80 and in the longitudinal vertical center of the tube 15. It is within the purview of my invention to support the prism 17 in any approved manner, though I prefer to employ for the purpose a pedestal 18 fixed on the 85 base 3 and having a socket 19 in its upper portion to receive the lower end of the prism 17.

Fixed on the base 3 and arranged in the casing 1 is a lamp socket 20 which is peculiar 90 in that its interior is smooth as brought out in Figure 3. The said lamp socket 20 is provided with the conventional or any other appropriate appurtenances 21 for the connection of wires in circuit with a source of electric energy, and when the shank of the incandescent electric lamp 22 is arranged in the said socket 20 it will be understood that one terminal of the filament 23 of the lamp will be arranged in the center of the lower 100 end of the shank and in contact with a complementary terminal on the base 3 while the other terminal of the filament 23 will be connected with the shank of the bulb which is of metal or other conductive material and is 105 exteriorly smooth and of circular form in cross section so as to snugly occupy and be adapted to turn about its axis in the circular portion of the socket 20. At its upper end the bulb of the lamp is provided with 110 the usual central protuberance 24, the said protuberance 24 being arranged in the socket

12 at the lower end of the plunger 11 with the result that the lamp will be subjected to slight tension so as to properly maintain it in position incident to its rotation.

- 5 Mounted on the lower portion of the lamp bulb is a circumferentially grooved clamp 25, and interposed between and connecting the said clamp 25 and a pulley 26 on the shaft 27 of the motor 4 is a belt 28, said belt 10 being disposed in the mentioned circumferential groove of the clamp 25. The clamp 25 is lined as indicated by 29 in Figure 5 with asbestos or other appropriate material with a view to averting breaking of the lamp 15 bulb when the clamp is placed thereon and also when the bulb and the clamp expand and contract. It will also be appreciated that the asbestos lining will prevent undue heating of the clamp 25 and will afford sufficient friction to assure turning of the lamp 20 about its axis with the clamp 25.

The prism 17 illustrated is a 60 degree prism, and therefore when the lamp is turned about its axis through the medium of the 25 motor 4, belt 28 and clamp 25, and the filament of the lamp is caused to glow, it will be apparent that as each of the filament stretches of the lamp comes in focus with the lenses and the prism, a spectrum of light 30 will be projected. The said spectrum will move in the direction in which the lamp is turned until it is out of focus when it will be followed by another stretch of filament, and so on, the rapidity of the passages of the 35 filament stretches being controlled by the speed at which the lamp is turned about its axis. Manifestly the strength of the light, the size of the prism and the strength of the lenses controls the distance to which the 40 spectrum can be projected. It will also be appreciated that the shape of the spectrum takes the form of the filament stretches.

As the lamp is rotated about its axis in the manner described with the filament glowing, it will be understood that the apparatus 45 will project a rapid succession of scintillating spectrums with the result that the apparatus will afford a free beautiful colored lighting effect which may be used to advantage in 50 show window and other illumination as well as in producing beautiful colored light effects on the stage and in other places.

At the left of Figure 1 I illustrate a plate 30 of frosted glass through which the light 55 may be projected when desired in order to produce a subdued lighting effect.

In Figure 6 I illustrate a modified prism 17^a characterized by walls 17^b and a filling 17^c of carbon disulphide. A prism such as 60 just described is desirable for some purposes inasmuch as it is calculated to lend increased brilliancy and strength to the light rays and to enhance the beauty of the varying or scintillating light afforded by the apparatus.

65 I have entered into a detail description of

the construction and relative arrangement of parts embraced in the present and preferred embodiment of my invention in order to impart a full, clear and exact understanding of the said embodiment. I do not desire, 70 however, to be understood as confining myself to the said specific construction and relative arrangement of parts inasmuch as in the future practice of the invention various changes and modifications may be made such 75 as fall within the scope of my invention as defined in my appended claims.

Having described my invention, what I 80 claim and desire to secure by Letters-Patent, is:—

1. In an illuminating apparatus, the combination of a lens, a prism located in front of the lens, and a rotary lamp located in rear of the lens and in line with the lens and prism, and having a filament stretch arranged to intersect a line extending through the lens and prism. 85

2. In an illuminating apparatus, the combination of a lens, a prism located in front of the lens, and a rotary incandescent electric 90 lamp located in rear of the lens and having filament stretches arranged to be moved one after the other across the focus of the lens.

3. In an illuminating apparatus, the combination of a lens, a prism located in front of 95 the lens, and a rotary incandescent electric lamp located in rear of the lens and having filament stretches arranged to be moved one after the other across the focus of the lens, with means comprised in the apparatus for 100 rotating the lamp about its axis.

4. In an illuminating apparatus, the combination of a lens, a prism located in front of the lens, and a rotary incandescent electric lamp located in rear of the lens and having 105 filament stretches arranged to be moved one after the other across the focus of the lens, with means comprised in the apparatus for rotating the lamp about its axis, and means for maintaining the lamp under 110 tension.

5. An illuminating apparatus comprising a casing, a lens tube carried in the forward wall of the casing and having double convex lenses at its ends, a prism maintained in 115 front of the lens tube, and a rotary incandescent electric lamp arranged in the casing and in rear of the lens tube and having filament stretches adapted to be moved one after the other across the focus of the lens tube. 120

6. An illuminating apparatus comprising a casing, a lens tube carried in the forward wall of the casing and having double convex lenses at its ends, a prism maintained in front of the lens tube, and a rotary incandescent electric lamp arranged in the casing and in rear of the lens tube and having filament stretches adapted to be moved one after the other across the focus of the lens tube; the bulb of the lamp being provided with a 125 130

rotating element, and the said element being connected with lamp-rotating means exteriorly of the casing.

7. In an illuminating apparatus, the combination of a lamp socket of circular form in cross section and smooth interior, an incandescent electric lamp having a smooth shank of circular form in cross section arranged in said socket, with a casing in which the lamp is arranged, a rotating element on the lamp bulb, lamp rotating means exteriorly of the casing and connected with said rotating element, and tensioning means in the casing and engaging the upper end portion 15 of the lamp bulb.

8. In an illuminating apparatus, the com-

bination of a casing, a prism supported in front of the casing, a lens tube carried by the front wall of the casing and having forward and rear double convex lenses, a reflector arranged in the casing in rear of the lens tube, a lamp socket, an incandescent electric lamp interposed between the lens tube and the reflector and having a shank journaled in said socket, a rotating element 20 on the bulb of the lamp, lamp rotating means exteriorly of the casing and connected with said element, and means about the lamp bulb and engaging said bulb to avert breaking of the same.

In testimony whereof I affix my signature.

FRANK D. COLLINS.
